UNITED STATES PATENT OFFICE

2,506,086

AUTOMATIC CABINET

Joseph F. Jess, Cleveland, Ohio

Application April 10, 1946, Serial No. 660,955

1. Claim. (Cl. 312—151)

1

This invention pertains to novel and useful improvements in an automatic cabinet and more especially has reference to a cabinet which is disposable in a concealed manner for the convenient disposition of articles contained therein and their protection from dirt or breakage.

The primary object of this invention is to provide a cabinet which may be entirely concealed and wherein the contents may be protected from dust and breakage.

An important object of the invention is the development of a cabinet in accordance with the foregoing object which may be automatically retracted into a concealed position.

An additional important object of the invention is the fabrication of a structure in conformity with the foregoing aim of the invention wherein simple but efficacious locking means are provided for maintaining the cabinet in selected extended position.

Other ancillary objects of the invention reside in the production of a concealed automatic cabinet which shall be attractive in appearance, compact, reliable in operation and convenient in use for the purposes intended.

These, together with numerous other objects of the invention which will later become apparent as the following description proceeds, are attained by my device, one embodiment of which has been illustrated by way of example only in the accompanying drawings, wherein:

Figure 1 is a front elevation of the cabinet in retracted position;

Figure 2 is a side elevational view showing the inner cabinet member in dotted lines in open position;

Figure 3 is a front elevational view showing the inner cabinet in extended position;

Figure 4 is a vertical transverse sectional view taken substantially upon the line 4—4 of Figure 3;

Figure 5 is a vertical sectional view taken substantially upon the line 5—5 of Figure 2;

Figure 6 is a horizontal sectional view taken substantially upon the line 6—6 of Figure 2;

Figure 7 is a horizontal sectional detail view taken upon the line 7—7 of Figure 1;

Figure 8 is a vertical sectional detail view upon the line 8—8 of Figure 1;

Figure 9 is a perspective view of a latch forming one element of my invention;

Figure 10 is a perspective view of the latch supporting brackets forming one element of my invention;

2

Figure 11 is a perspective view of the latch pivot constituting a detail of the invention;

Figure 12 is a perspective view of the latch spring in accordance with my invention;

Figure 13 is a perspective view of the inner cabinet member; and

Figure 14 is a perspective view of a shelf of the inner cabinet member.

Referring now more particularly to the attached drawings, there is shown an outer casing member 10 in which is slidably disposed for vertical movement an inner cabinet member 12. The upper end of the outer casing member is closed while the lower end is open to permit the extension and withdrawal of the inner cabinet member therefrom. The inner cabinet member is of less width than the casing member whereby lateral vertical spaces are provided therebetween for a purpose to be set forth hereinafter. As shown best in Figures 5 and 13, the inner cabinet member contains a plurality of shelves 14 and a bottom member 16 of a width equal to the outside width of the outer casing member whereby in closed position the member 16 may be seated flush against the lower side of the outer casing member and impart a symmetrical appearance thereto. Secured to each side of the cabinet adjacent the upper end thereof are pairs of angle brackets 18 centrally apertured as at 20 for a purpose to be set forth hereinafter. Although I have shown two of these brackets upon each side of the cabinet it will be evident that any suitable number, including a single bracket to each side may be provided. The sides of the outer casing member are inturned at their lower ends to form a flange 22 adapted to snugly fit in the vertical space between the inner cabinet and the casing. Vertical guide rods 24 are disposed in the vertical spaces referred to above and are rigidly secured in any suitable manner to the upper surface and the inturned flange 22 of the outer casing member and pass loosely through the apertures 20 in the lugs 18. These rods constitute guides for the lugs 18 and for a coiled spring 26 which is seated between the lower flange 22 and the lower surface of the angle brackets 18.

From the construction as so far described, it will be seen that the spring means 26 yieldingly urges the inner cabinet member up into the casing member in closed and concealed position. A suitable hand hold 28 is recessed or notched into the member 16 to afford a convenient means for extracting the member from its recess in the outer casing against the opposition of the spring 26. Suitably secured upon each side of the cabinet

member and attached thereto are a pair of rack bars 30 arranged in vertically disposed position and receivable in the lateral space between the inner and outer cabinet members.

As shown in detail in Figure 8, a latch mechanism is secured to the front of the outer casing member and disposed in the lateral space between the inner and outer members. This latch mechanism comprises a pair of triangular shaped bracket members 32 secured to the back of the front wall of the outer member and having a transverse pivot pin 34 upon which is fulcrumed a bell crank 36 having a detent 38 engageable with the rack bar 30. The upper arm of the bell crank is turned forwardly as at 40 and has a knob 42, the projection 40 extending through a cup shaped depression in the front wall of member 10 as indicated at 44 for convenient manipulation by the user of the cabinet. A coil spring member 46 is suitably disposed upon the pivot pin 34 and is engaged with the bell crank to bias the latter in a clockwise direction into engagement with the rack 30. As shown in Figure 14, the shelves 14 of the cabinet member may be provided with a series of grooves 46 for the purpose of positioning and retaining plates for china in the cabinet, such a use being indicated in Figure 4 wherein the dotted line construction 48 indicates a plate positioned in the groove and tilted back against the back wall of the cabinet.

In order to improve its appearance the lower surface of the inner cabinet member 14 may be chamfered as at 50, it being understood that the cabinet set forth hereinbefore is intended primarily for mounting upon walls or the like whereby the cabinet portion may be lowered and extended therefrom to any desired degree and in adjustable position for displaying its contents.

Although I have indicated as one possible use of my cabinet the storing of china and the like, it is obvious that it is equally adapted for the reception of books, the disposal of liquors and the like and in general for any use where it is de-

sirable that its contents be available for instant use and yet capable of being compactly and neatly stored.

It is to be understood that I do not limit myself to the exact construction shown and described in this application but that I may avail myself of any suitable modifications falling within the scope of the appended claim.

I claim as my invention:

5 10 In the cabinet, a casing, an inner cabinet member slidably disposed within said casing, laterally extending lugs secured to the upper sides of said inner cabinet and engaging the inner sides of said casing for guiding and centering the 15 sliding movement of said inner cabinet, vertical guides secured to the casing and extending through said lugs, spring means mounted on said guides normally biasing said cabinet into said casing, and latch means comprising a rack 20 bar secured to said cabinet, a bell crank lever pivoted in said casing, said bell crank including a detent at one end thereof and a spring encircling said pivot and biasing said detent into engagement with said rack in order to adjust 25 the cabinet in predetermined positions.
